No. 37,381.

Patented March 28, 1905.

UNITED STATES PATENT OFFICE.

BYRON B. GOLDSMITH, OF NEW YORK, N. Y.

DESIGN FOR A LEAD-PENCIL TIP.

SPECIFICATION forming part of Design No. 37,381, dated March 28, 1905.

Application filed December 22, 1903. Serial No. 186,260. Term of patent 14 years.

To all whom it may concern:

Be it known that I, BYRON B. GOLDSMITH, a citizen of the United States, residing at New York, in the county and State of New York, have invented a new, original, and ornamental 5 Design for Lead-Pencil Tips, of which the following is a specification, reference being had to the accompanying drawing, forming part thereof.

The figure shows a perspective view of a 10 lead-pencil tip embodying my design.

I claim—

The ornamental design for a lead-pencil tip, as shown.

BYRON B. GOLDSMITH.
